UNITED STATES PATENT OFFICE.

JOHN M. DEXTER, OF ELMIRA, NEW YORK.

LAMP.

SPECIFICATION forming part of Letters Patent No. 236,996, dated January 25, 1881.

Application filed October 19, 1880. (No model.)

To all whom it may concern:

Be it known that I, JOHN M. DEXTER, of Elmira, Chemung county, New York, have invented certain Improvements in Lamps, of 5 which the following is the specification.

The object of my invention is a lamp constructed, as fully described hereinafter, so as to avoid the difficulties incident to the ordinary modes of connecting the burners to the 10 reservoirs and the latter to the stems.

In the drawings, Figure 1 is a sectional elevation of a lamp reservoir and socket, showing my improvement. Fig. 2 is a plan of Fig. 1 with the shield removed. Fig. 3 is an enlarged section on the line 1 2, Fig. 2; Fig. 4, 15 a plan of the reservoir, the metal fixtures being detached. Fig. 5 is a sectional view of a modification, and Fig. 6 a detached view of the fastening-key.

20 The reservoir may be of any desired material, as glass or porcelain, and of any suitable form. I however prefer to make it with a depressed top, *a*, so as to direct any oil which may run down from the burner toward the 25 central orifice, *x*, surrounded by a flange, *b*, having channels or notches *e*, through which the oil will descend to the reservoir, as set forth in a separate application for Letters Patent filed October 8, 1880.

30 The burner-socket consists of a short tube, *B*, threaded internally to receive the hub of the burner, and provided with an annular exterior shoulder, *c*, having its bearing upon the edge of the flange *b*. Near the lower edge of the tube are lugs *f*, so placed that they may be passed through the notches *e* on fitting the tube in its socket, the slight turning of the tube, after passing the same, with its lugs, through 35 the notches, bringing the lugs below the top 40 of the reservoir and preventing the removal of the tube. The shoulder *c* has a notch, *i*, cut through it to receive a key, *D*, with a large head, which key, when passed through the head, which key, when passed through the notch *i* and one of the channels *e*, will hold 45 the tube from turning and prevent its removal. The tube is thus fixed to the reservoir; but to 50 secure an absolutely steady connection, as well as cover up and conceal the joint and present a more sightly and finished appearance, a shield, *E*, is used, consisting of an annular rim with a central threaded opening adapted to threads on the tube *B*, or with notches and inclines, Fig. 1, which bear beneath studs *m* 55 on the tube, and when the shield is turned raise the tube until the lugs *f* bear firmly

against the top of the reservoir, and all the parts are held tightly in place. When thus secured the tube is held in place against all forces ordinarily liable to dislodge it, while the accidents to which ordinary lamps provided with tubes cemented to the reservoir are liable cannot here occur.

The shield *E*, by being waved or notched at its edge, will permit the oil falling on the top *a* to flow toward the channels *e* and back to the 60 reservoir.

It will be apparent that the tube *B* may be readily removed by detaching shield *E* and the key *D* and turning the tube until the lugs *f* coincide with the channels *e*.

70 The thimble *F*, for receiving the filling-cap, is attached in the same way, as shown in Fig. 1.

A metal thimble, *J*, having an external bead, is embedded in the body of metal when the reservoir is molded, thus securing a firm 75 attachment, the thimble having internal threads adapted to those of the standard or stem which supports the reservoir.

The rim or flange *b* imparts steadiness to the tube *B* and holds it so firmly that the use 80 of cement is dispensed with, while the notches *e* permit the oil on the top *a* to pass into the reservoir, notwithstanding this flange.

I do not claim, broadly, a notched flange combined with an attachment having external 85 lugs; but

I claim—

1. The combination of the reservoir having a burner-opening with a channeled flange, a tube having an external notched rib or 90 flange and lugs adapted to said channels, and a key adapted to the rib and to fit one of the channels, as set forth.

2. The combination of the notched reservoir, tube provided with a flange and projections *f*, and shield *E*, adapted for attachment 95 to said tube and bearing on the reservoir, substantially as set forth.

3. The combination of the reservoir, tube, and shield *E*, screwed upon and adapted to 100 said tube and bearing on the reservoir, substantially as set forth.

In testimony whereof I have signed my name to this specification in the presence of two subscribing witnesses.

JOHN M. DEXTER.
